US0D1046914S

(12) **United States Design Patent** (10) Patent No.: **US D1,046,914 S**
(45) Date of Patent: ** Oct. 15, 2024

(54) **DISPLAY SCREEN OR PORTION THEREOF
WITH A GRAPHICAL USER INTERFACE
FOR A VISUALIZATION OF A SYSTEM
INPUT STATUS**

(71) Applicant: **SPLUNK Inc.**, San Francisco, CA (US)

(72) Inventors: **Iryna Vogler-Ivashchanka**, Los Altos, CA (US); **Mei Chun Yeh**, San Francisco, CA (US); **Tatsuya Hama**, North Vancouver (CA)

(73) Assignee: **SPLUNK Inc.**, San Francisco, CA (US)

(**) Term: **15 Years**

(21) Appl. No.: **29/858,423**

(22) Filed: **Oct. 31, 2022**

(51) LOC (14) Cl. **14-04**

(52) U.S. Cl.

USPC **D14/492**; D14/486

(57) **CLAIM**

The ornamental design for a display screen or portion thereof with a graphical user interface for a visualization of a system input status as shown and described.

DESCRIPTION

The FIGURE is a display screen or portion thereof with a graphical user interface for a visualization of a system input status, showing our new design.

The broken lines represent a display screen or portion thereof and form no part of the claimed design. The remaining broken lines show portions of a graphical user interface for a visualization of a system input status and form no part of the claimed design.
